FEELER-MOTION FOR LOOMS.

1,208,712.

Specification of Letters Patent. Patented Dec. 12, 1916.

Appl. 4th filed March 9, 1916. Serial No. 83,186.

To all whom it may concern:

Be it known that I, ALONZO E. RHOADES, a citizen of the United States, residing at Hopedale, in the county of Worcester and 5 State of Massachusetts, have invented an Improvement in Feeler-Motions for Looms, of which the following description, in connection with the accompanying drawings, is a specification, like characters on the drawings representing like parts.

The invention to be hereinafter described relates to feeler motions for looms, whereby when the filling in the active shuttle becomes substantially exhausted, a train of 15 mechanism is set for effecting a change in the loom operation, such for instance, as replenishment of the filling. Devices of this character must be sensitive and for the best results, should call for filling replenishment when only sufficient filling remains 20 upon the bobbin or carrier in the shuttle to insure a full pick being laid in the shed under proper tension upon the last trip of the shuttle preceding replenishment. In order 25 that proper detection may be made by the feeler, the shuttle and filling carrier or bobbin therein should be presented to the feeler on each detecting beat in the same or substantially the same position. Preferably, 30 this position should be such that the feeler may perform its function by contacting with the filling or bobbin upon an element of the cylindrical surface of either which reaches the most frontward position on the 35 beat-up. When the feeler acts horizontally, this element will of course, be in a horizontal plane passing through the longitudinal axis of the bobbin. The shuttle, however, does not always occupy the same vertical 40 position in the shuttle-box, owing to the fact that the shuttle is usually somewhat less in external vertical height than the internal height of the shuttle-box. In other words, the shuttle will sometimes be high and at 45 other times be low in the shuttle-box, with the result that the feeler will not always engage the same element of the cylindrical surface of the filling or bobbin. This will cause inaccuracy in detection of filling exhaustion, and replenishment is liable to be called when there still remains a working supply of filling in the shuttle.

An important feature of the present invention, therefore, consists in providing two

feeler members vertically separated a distance such that when the shuttle is high in the box, the upper feeler member will detect the condition of the filling and when the shuttle is low in the box, the lower feeler member will similarly act.

Another important feature of the invention consists in a feeler guard between the upper and lower feeler members and having a filling engaging end projecting normally beyond the ends of the feeler members and 60 movable from guarding position just prior to the time of or on the near approach to substantial exhaustion of filling. This feature of the invention is preferably carried into effect by a guard between the upper and lower feeler members having an end, which, when a working supply of filling is present in the shuttle will engage the filling mass and be held in guarding position, thereby, 65 as the lay beats up; but when the mass of filling approaches near to substantial exhaustion and it is desired that the upper and lower feeler members be permitted to perform their detecting function, it will permit 70 the guard to be moved from guarding position.

The above and other features of the invention will be hereinafter described in connection with the accompanying drawings showing one good, practical form of the invention, and will then be definitely claimed.

In the drawings:—Figure 1 is a perspective view of a feeler motion embodying one form of the present invention, the lay and parts of the loom which coat therewith being omitted, as such parts are well understood by those skilled in the art; Fig. 2 is a perspective view showing the action of the feeler motion when a working supply of filling is present in the shuttle, some of the parts being omitted and others broken away for clearness of illustration; Fig. 3 is a view similar to that of Fig. 2, showing the action of parts when the filling has become substantially exhausted; Fig. 4 is a sectional view through the end of the feeler and transversely of the filling carrier or bobbin, showing the action of the feeler when the filling carrier or bobbin is in low position in the shuttle-box; Fig. 5 is a view similar to that of Fig. 4, showing the action of parts when the filling carrier or bobbin is in high position in the shuttle-box; and Fig. 6 shows

the upper and lower feeler members detached.

The feeler stand comprises a base portion 1 to which is secured by suitable means, such as the screws 2, a cover 3 having the usual recess 4 to receive the shank portion of the feeler slide 5, a spring 6, as usual in such constructions, being employed for normally holding the feeler slide in rearward position, but yielding frontward on the detecting beat of the lay to permit forward movement of the feeler slide.

Rising from the feeler slide 5 are the webs or lugs 7 between which, as at 8, is pivotally mounted the arm 9 which, for identification, will hereinafter be known as the actuator. Extending rearward from the actuator 9 is the projection 10 beneath which is a spring 11 which normally acts to hold the actuator 10 with its bifurcated end portion 12 in lowered position, substantially as indicated in Fig. 2.

Extending transversely of the feeler stand is an arm 13 which, for identification, will hereinafter be known as the controller. The controller 13 passes through the slotted end portion 14 of an arm 15, generally known in the art as a transmitter, the construction being such that when the controller 13 is moved frontward it will ride over the cam portion 16 of the transmitter and depress the adjacent end portion thereof to thereby, through suitable connections well understood in the art, initiate filling replenishment or other change in the loom operation.

As hereinbefore pointed out, the shuttle and, perforce, the bobbin or filling carrier therein, does not always occupy the same vertical position when it is received in the box adjacent the feeler. Sometimes it will be high and sometimes it will be low in the shuttle-box, due to the fact that the vertical dimensions of the shuttle itself are smaller than the vertical dimensions of the shuttle-box.

Regardless of the vertical position of the shuttle and perforce, the filling carrier in the shuttle-box, it is desirable that the feeler shall act upon the filling mass or bobbin as the case may be, along an element contained in a plane passing horizontally through the axis of the bobbin. As a means to this end, the present invention contemplates two feeler members arranged in separated vertical position such that when the shuttle is high in the box, the upper feeler member will perform its detecting function, and when the shuttle is low in the box, the lower feeler member will similarly act, the result being that detection of filling exhaustion will be more accurately and uniformly attained, and filling replenishment be effected only when the filling has reached the desired degree of exhaustion. In carrying this feature of the invention into practical effect in the present instance, the feeler slide has

its rear end portion provided with the upper and lower impinging members 17 and 18. These are best formed by narrowing the end portion 18 of the feeler slide itself and mounting thereon the plate 19 which may, for convenience, be integrally formed as part of the web 7 hereinbefore described.

Extending longitudinally of the feeler slide are the guideways in which are received the upper and lower feeler members 20 and 21, which in the present instance, are shown as the penetrating members each being provided with a penetrating end 22 adapted to sink into the filling when a working supply is present, and to be pushed forward by the more dense surface of the bobbin 23 itself when the filling has become practically exhausted, and the lay makes its detecting beat. The guideways for the upper and lower feeler members 20 and 21 may be formed in any usual manner and as illustrated, the guide way for the lower feeler member is formed on the feeler slide, while the guideway for the upper feeler member 20 is formed in the plate 19, substantially as indicated in Figs. 2, 3, 4 and 5, the construction being such that when a working supply of filling is present on a detecting beat, the upper or lower penetrating member 20 or 21 will engage and sink into the filling mass, according to the vertical position of the shuttle in the box, and fail to be moved relatively to its accompanying upper or lower impinging member 17, 18, but when the filling has become substantially exhausted, the upper or lower penetrating member will engage the more dense surface of the bobbin itself, according as the shuttle is in high or low position in the box, and be moved relatively to its adjacent impinging member, and through the means to be described, thereby initiate filling replenishment on the continued forward movement of the lay.

Secured to the actuator 9 is the heel 24 having a toe portion 25 resting upon the top surface of the feeler slide 5 when the parts are in position as indicated in Fig. 2. The lower feeler member 21 is provided with a heel-engaging portion 26 and similarly, the upper feeler member 20 is provided with a heel-engaging portion 27. Inasmuch as the feeler members 20 and 21 are separated in vertical planes appropriate to the play of the shuttle in the shuttle-box for the purposes hereinbefore described, the heel-engaging portions of the feeler members are so formed as to maintain said feeler members in parallel relation. To this end, the lower feeler member 21 has its outer end portion provided with a head 28, the flat upper surface of which provides a seat for the end 29 of the upper feeler member 20, the construction being such that either of said feeler members when moved rela-

tively to its adjacent impinging member longitudinally of the feeler slide, will act upon the heel 24 of the actuator 9 and lift its bifurcated end portion 12 into position 5 to engage the controller 13 so that on further forward movement of the feeler slide due to the advancing lay, the controller 13 will be moved to initiate filling replenishment.

10 It is desirable that the detecting function of the feeler be performed only when the filling has reached a degree near to substantial exhaustion so that all danger of prematurely effecting filling replenishment by 15 improper action of the feeler may be eliminated. To this end, the present invention contemplates the provision of a feeler guard between the upper and lower feeler members 20 and 21, which, during the presence 20 of a working supply of filling, will be maintained in normal guarding position projecting beyond the ends of the feeler members; but when the filling has neared substantial exhaustion, and it is desired that the feeling 25 function of the feelers shall be permitted, is moved from guarding position. To this end, there is pivotally mounted on the feeler slide, the feeler guard 30, the end portion 31 of which enters a recess or slot 32 between 30 the upper and lower feeler members 20, 21, said portion 31 of the feeler guard being provided with a series of teeth or roughened portions 33 normally projecting beyond the ends 22 of the feeler members 20 and 21 and 35 adapted to be first engaged by the mass of filling when a working supply is present. In the present instance, the feeler guard 30 is pivotally mounted in a lug 34 which may be conveniently formed as a part of the 40 webs 7 secured to the feeler slide. The lug 34 extends laterally from the feeler slide so that the feeler guard 30 has its pivot offset from its filling-engaging portion 33, the construction being such that upon the 45 detecting beat of the lay when a working supply of filling is present, the teeth 33 of the feeler guard will engage and sink into the filling mass and be held by such filling mass from movement about its pivotal 50 mounting as the lay beats up, thereby acting as a guard for the feeler members 20 and 21 during normal loom operation; but when the filling has approached near to substantial exhaustion and only a few turns 55 of filling remain upon the bobbin 23, the teeth 33 of the guard will engage the more dense surface of the bobbin 23, and on further forward movement of the lay, the forward push of the bobbin will cause the 60 feeler guard to turn upon its pivotal mounting and expose the upper and lower feeler members 21 and 22 to their detecting function, and when the filling has reached the desired degree of exhaustion, one of said 65 feeler members, depending upon the posi-

tion of the shuttle in the box, will be moved relatively to its adjacent impinging member, thereby positioning the actuator 9 operatively with relation to the controller 13 to effect filling replenishment upon further 70 advancing movement of the lay and feeler slide.

When the feeler slide is moved to its rearward position after a replenishing operation due to substantial exhaustion of filling, it 75 is desirable that the feeler guard be returned to feeler-guarding position; and to this end the feeler 30 has a laterally-projecting toe portion 35 adapted to engage the end 36 of a rod 37 mounted in suitable bearings 38 in the feeler stand and normally pressed rearward by a spring 39, the construction being such that while the rod 37, which may be known as the feeler-guard-resetting device, is movable forward against 80 the action of its spring 39, the said spring normally tends to hold the said rod 37 in its feeler-guard-resetting position as indicated in Fig. 1. The rearward position of the feeler-guard-resetting device 37 may be conveniently adjusted by means of adjusting nuts 40 secured to the front end portion of the rod 37. In order that the feeler guard 30, when being reset by the rod 37, may not be turned too far by the action of said rod, 85 the feeler guard is provided with a toe portion 31 which may contact with the adjacent web 7 rising from the feeler slide 5.

From the construction described, it will be seen that the feeler guard is movable in 100 a direction longitudinally of the shuttle on a detecting beat when the supply of filling approaches substantial exhaustion, and such movement is made between the upper and lower feeler members 20 and 21, over-movement of the feeler guard in said direction being prevented by suitable means such as the shoulder 42 which may engage the rear part of the feeler slide when the feeler guard has been moved from its normal guarding 105 position.

While the present invention has been described in connection with a feeler of the penetrating and impinging type, it is to be understood that the invention is not necessarily limited thereto, although it offers special advantages in connection with such type of feeler, and by the use of the terms "upper and lower feeler members" in the 115 claims, applicant intends to include not only 120 the feeler members of the penetrating type, but feeler members of other varieties.

What is claimed is:—

1. A feeler motion for looms, comprising an upper feeler member and a lower feeler member each adapted to enter the same shuttle on a detecting beat and feel for the filling therein, a guard to prevent detecting action by either feeler member until the filling nears substantial exhaustion, and means ren- 130

dered effective upon detection of substantial exhaustion of filling by either feeler member to initiate filling replenishment.

2. A feeler motion for looms, comprising an upper feeler member to enter the shuttle and detect the condition of filling therein when the filling carrier is in a relatively high position in the shuttle-box, a lower feeler member to enter the shuttle and detect the condition of the filling when the filling carrier is in a relatively low position in the shuttle-box, means adapted to be moved to effect filling replenishment upon detection of substantial exhaustion of filling by either of said feeler members.
3. A feeler motion for looms, comprising an upper and a lower feeler member each adapted to enter the shuttle on a detecting beat and feel for the filling, and a guard between the upper and lower feeler members having a filling engaging end extending beyond the feeler members and moved from guarding position when the filling nears substantial exhaustion.
4. A feeler motion for looms, comprising two feeler members to enter the same shuttle on a detecting beat, one of said feeler members acting to detect substantial exhaustion of filling when the shuttle is high in the shuttle-box and the other member acting to detect substantial exhaustion of filling when the shuttle is low in the shuttle-box, and means rendered effective by detecting movement of either of said feeler members to initiate filling replenishment.
5. A feeler motion for looms, comprising two feeler members to enter the same shuttle on a detecting beat, one of said feeler members acting to detect substantial exhaustion of filling when the shuttle is high in the shuttle-box and the other member acting to detect substantial exhaustion of filling when the shuttle is low in the shuttle-box, a guard between the said two feeler members and movable from guarding position when the filling nears substantial exhaustion to permit said feeler members to detect substantial exhaustion, and means rendered effective by detecting movement of either of said feeler members to initiate filling replenishment.
6. In a loom, the combination of a feeler, comprising an impinging member and two independently movable penetrating members arranged in different horizontal planes, the upper of said penetrating members being adapted to detect substantial exhaustion of filling when the shuttle is high in the shuttle-box and the lower penetrating member being adapted to detect substantial exhaustion of filling when the shuttle is low in the shuttle-box, and means controlled by exhaustion indication by either of said penetrating members for initiating filling replenishment.
7. In a loom, the combination of a feeler, comprising an impinging member and two independently movable penetrating members arranged in different horizontal planes, the upper of said penetrating members being adapted to detect substantial exhaustion of filling when the shuttle is high in the shuttle-box and the lower penetrating member being adapted to detect substantial exhaustion of filling when the shuttle is low in the shuttle-box, a guard between the upper and lower penetrating members for preventing detecting action by either until the filling nears substantial exhaustion, and means controlled by exhaustion indication by either of said penetrating members for initiating filling replenishment.
8. In a feeler motion for looms, the combination of a feeler comprising an impinging member, upper and lower penetrating members, a guard between the upper and lower penetrating members having a filling engaging end extending beyond said feeler members and movable from guarding position by the forward push of the bobbin when the filling nears substantial exhaustion to permit the upper or lower penetrating member of the feeler to detect the condition of the filling according to the height of the shuttle in the shuttle-box.
9. A feeler motion for looms, comprising a feeler slide having an impinging end, an upper and a lower penetrating member mounted for longitudinal movement on the slide and adapted to penetrate or sink into the filling when a working supply is present on a detecting beat, said slide having upper and lower guideways for the penetrating members, an actuator independent of the upper and lower penetrating members and adapted to be moved by either upon detection of substantial exhaustion, and means for initiating filling replenishment.
10. In a feeler motion, the combination of a feeler slide having a filling engaging end portion, upper and lower guideways extending longitudinally of the slide, upper and lower feeler members movable in said guideways, and an actuator having a heel adapted to be engaged by the front end portion of the upper and lower feeler members and movable by either into position for initiating filling replenishment upon detection of substantial exhaustion by either feeler member.
11. In a feeler motion, the combination of a feeler slide having a filling engaging end portion, upper and lower guideways extending longitudinally of the slide, upper and lower feeler members movable in said guideways, said filling engaging end portion of the feeler slide having a recess between the upper and lower feeler members, a feeler guard movable in said recess between the feeler members, and an actuator

having a heel adapted to be engaged by the front end portion of the upper and lower feeler members and movable by either into position for initiating filling replenishment upon detection of substantial exhaustion by either feeler member.

12. In a feeler motion for looms, a feeler slide having an impinging end portion provided with a slot, a feeler member above and a feeler member below said slot, and a feeler guard normally projecting beyond the ends of the feeler members and adapted to be moved into said slot when the filling nears substantial exhaustion.

13. In a feeler motion for looms, the combination of a feeler slide, an actuator carried by said slide and having a heel, upper and lower feeler members adapted to act independently to detect filling exhaustion when the shuttle is in high and low positions respectively, and each of said feeler members having a heel engaging end for operatively positioning the actuator when either of said feeler members detects substantial exhaustion of filling.

In testimony whereof, I have signed my name to this specification.

ALONZO E. RHOADES.
